CHARLES G. SMITH, OF MEDFORD, MASSACHUSETTS, ASSIGNOR TO RAYTHEON INC.,
OF CAMBRIDGE, MASSACHUSETTS, A CORPORATION OF MASSACHUSETTS

RECTIFIER

Application filed January 22, 1927. Serial No. 162,780.

This invention relates generally to thermionic devices and in particular to rectifiers employing two or more electrodes in juxtaposed relation, one of which includes a filamentary cathode. In order to minimize impedance and consequent voltage drop between elements, it has been proposed to utilize the vapor of certain alkaline substances introduced into the envelope either by distillation, in which case the electrodes or the inner surface or both of envelope acquire a relatively thick coat of the material or by providing solid electrodes of the material. However, not only has difficulty attended the introduction of material, but in operation, rectifiers containing a certain class of substance calculated to reduce internal losses have shown marked inferiority for one of several reasons. In the matter of distillation the process is quite tedious, expensive and prohibitory in the manufacture of rectifiers on a large scale. Furthermore, the presence of an alkali coat derived by distillation and forming in appreciable thickness on elements in the tube other than the active electrodes, is not conducive to consistent results and may expose some of the inactive elements to attack by the material. The art, in turning for a solution of the problem to solid alkali electrodes, found that when subjected to electron impact, they disintegrate rapidly particularly when surrounded by gas.

Now, I propose a rectifier containing a filamentary cathode and in which the benefits of alkali metal are secured in substantial degree without the disadvantages noted above. Briefly, this is accomplished by immersing the cathode in an alkali vapor, the volume of which is substantially defined; preferably, the vapor is confined within the other electrode. By constraining the fluid to a given region removed from the leading-in conductors and the glass envelope and other insulating elements, the deleterious effects noted above, are precluded.

Accordingly, the primary object of my invention is to provide a rectifier of relatively low impedance and potential drop between electrodes. Another object is to increase the saturation current from the heated cathode.

A still further object is to provide for the purposes stated, the practical utilization of alkali metals in general. Other objects and features will be apparent upon perusal of the following description when considered in view of the accompanying drawing in which,

The figure represents a preferred embodiment of the invention.

In the figure, numeral 1 indicates the usual glass envelope containing cathode 2 and anode 3, each being of a suitable refractory material. The cathode comprises a filamentary member depending from rigid conductors 4, the latter being supported by the press. The anode or plate member 3 is similarly held in position by a conductor 5 fused in the glass envelope. It will be noted that the anode takes the general form of a cylinder totally closed at both ends, except for a small opening of sufficient dimension for the cathode leads. It is apparent that my invention is not limited to a particular shape of anode, the essential point being that it is practically or substantially totally enclosed. During manufacture, the thermionic device is held upright with the press in the lower position as shown, and prior to assembly of electrodes, a piece of metallic lithium 8 is placed on the horizontal member of the anode. The filament is then positioned within the anode and the tube evacuated in the usual manner. When the cathode is energized and potential applied between electrodes, electrons traveling to the plate heat the same until an appreciable vapor pressure of lithium is built up within the metallic chamber, whereupon the voltage drop falls off and heating diminishes. This decrease in voltage continues until a value is reached such that the losses in the tube remain practically constant. Now it appears that lithium melts at 186° C. approximately; boils at 1400° C. approximately; and has a specific gravity of about .5. The low melting point, combined with the relatively high surface tension of this substance when molten, offers an extreme advantage in readily providing a liquid film that spreads evenly over the inner surface of the heated anode. This coat presents a surface which is particularly useful in facilitating clean-up of the various gases without

100

the necessity of excessive heating. The high volatilization temperature of lithium not only minimizes the possibility of arcing on reversed potential but also prevents excessive distillation of the alkali substance from the active portion of the tube. The enclosed anode serves to confine the body of vapor to a region closely associated with a filament, thus preventing its general dissemination throughout the envelope where it may affect elements external to the anode and cause local discharges or wandering of the arc and other irregularities. Furthermore, by providing a screen between the envelope and incandescent cathode, photo-electric effects and other electrical phenomena resulting from the presence of a small lithium deposit which may have escaped through the aperture in vaporous form and condensed on the envelope, are prevented. However, ordinarily all vapor will be chiefly confined to the space within the hollow anode.

From the foregoing it will be understood that rectification proceeds in the usual manner but the space between anode and cathode is permeated with alkali vapor resulting in a relatively low impedance between electrodes; the internal losses of the unilateral conductor are also reduced in substantial degree. It will be apparent that in the final rectifier any of the usual gases may be admitted to the envelope. If desired, the rectifier may be provided with a base 6 of suitable design and plugs 7 to make ready contact with external circuits.

I claim:

1. A rectifier comprising an evacuated envelope, electrodes therein, one electrode adapted to emit electrons, another electrode to function as an anode and substantially totally enclosing the first named electrode, and a quantity of lithium, substantially all of which is within the anode.

2. A rectifier comprising an evacuated envelope, electrodes therein, one electrode adapted to emit electrons, another electrode to function as an anode and almost totally enclosing the first named electrode, and a quantity of solid alkali metal inserted within the anode.

Signed by me at Cambridge, Massachusetts, this 10th day of January, 1927.

CHARLES G. SMITH.
